Specification for Design.

Patented Feb. 20, 1912.

Application filed October 5, 1911. Serial No. 653,054. Term of patent 7 years.

To all whom it may concern:

Be it known that I, CHARLES E. J. LANG, a citizen of the United States, and a resident of Cleveland, county of Cuyahoga, and State of Ohio, have invented a new, original, and ornamental Design for Vehicle-Bodies, of which the following is a specification, reference being had to the accompanying drawings, forming part thereof.

In said annexed drawings:—Figure 1 is a front elevation of a vehicle body showing my new and ornamental design; Fig. 2 is a

rear elevation of the same; and Fig. 3 is a side elevation of the vehicle body shown in Figs. 1 and 2.

I claim:—

The ornamental design for a vehicle body, as shown.

Signed by me, this 2 day of October, 1911.

CHAS. E. J. LANG.
